HAT HOLDER

Ernest W. Pfeil, Milwaukee, Wis.

Application September 12, 1947, Serial No. 773,697

4 Claims. (Cl. 211—32)

1

This invention appertains to a holder for men's hats and is an improvement over my prior invention illustrated in my pending application, Serial No. 702,935, filed October 12, 1946.

One of the primary objects of my present invention is to provide bendable lips on the opposite sides of the hat supporting yoke, whereby different sizes of hat crowns can be effectively accommodated and efficiently held with a limited resilient grip.

Another salient object of my invention is to provide novel means struck out from the panel or face plate for detachably engaging the yoke to hold the same at the desired hat receiving angle relative to the panel, whereby the use of extraneous cords, and the like, for such purpose is eliminated.

A further important object of my invention is the provision of a struck out bendable tongue on the lower part of a hat receiving yoke for engaging the panel, so that an additional bottom supporting bracket will be had for the yoke.

With these and other objects in view, the invention consists in the novel construction, arrangement and formation of parts, as will be hereinafter more specifically described and claimed, and illustrated in the accompanying drawings, in which drawings:

Figure 1 is a front elevational view of my improved hat holder showing the same cut from a single blank of sheet material.

Figure 2 is a view similar to Figure 1, but showing the hat receiving yoke swung out to its operative position and receiving a hat, parts of the view being shown broken away and in section.

Figure 3 is a horizontal, sectional view taken on the line 3—3 of Figure 2, looking in the direction of the arrows.

Figure 4 is a vertical, sectional view through the hat holder, taken on the line 4—4 of Figure 2, looking in the direction of the arrows.

Figure 5 is a fragmentary, detailed, perspective view showing the use of cords for limiting the outward swinging movement of the hat receiving yoke.

Referring to the drawing in detail wherein similar reference characters designate corresponding parts throughout the several views, the letter H generally indicates my improved hat holder.

The hat holder H is constructed along the same general line as the hat holder shown in my pending application, and hence, the same is cut from a single sheet of material, such as

2

cardboard. The hat holder includes a front panel or face plate 6.

Struck out of the panel 6 is front supporting frame or yoke 7 for supporting a hat 8. The yoke is of a U-shape in front elevation and is cut from the panel 6 and is free from said panel at all points with the exception of the lower edge thereof so as to provide a hinge 9. If desired, the yoke 7 above the hinge 9 can be scored or otherwise weakened as at 10 parallel with said hinge, so that an offset connecting portion 11 can be provided. This offset connection portion 11 can have struck out therefrom a bendable tab 12, which is adapted to engage the front face of the panel 6 when the yoke is swung out, and this tab forms an additional supporting bracket for the yoke.

While the yoke 7 can be limited in its outward swinging movement by cords 13 as shown in Figure 5 and illustrated in my pending application, it is preferred to provide arms 14 struck out from the panel for limiting the outward swinging movement of the yoke. The arms 14 have formed on their lower ends inwardly projecting fingers 15. Consequently, when the yoke 7 is swung out from the panel 6, and the arms 14 are extended, the fingers 15 can engage the outer face of the yoke to limit the outward swinging movement of the yoke.

As in that form of my invention shown in the pending application, the hat 8 is adapted to be placed against the front panel 6 and slid down within the yoke 7. The brim of the hat fits between the panel and the yoke, and the crown of the hat is received directly in the yoke.

It has been found advantageous to provide means for accommodating different sizes of hat crowns and to slightly, resiliently engage the crown so as to prevent accidental displacement of the hat from the holder. Consequently, in accordance with my present invention, I provide substantially vertical scored lines 16 on the upright portions of the yoke 7 so as to provide inwardly bendable hat crown engaging lips 17. In order to further form the lips and to permit this inward bending, the yoke 7 can be cut inwardly and arcuately as at 18 to meet the scored lines 16 on opposite sides of the yoke.

With the bending back of the lips 18, a somewhat resilient connection is had, and hence, when the hat is inserted in the yoke, these lips will give according to the size of the crown of the hat. Thus, various sizes of crowns can be effectively received with a yielding pressure.

As is clearly shown in Figure 4, thumb tacks,

or the like, 19 can be pushed through the panel 6, so that the hat holder can be secured to a wall, the inside face of a closet door, or the like.

Changes in details may be made without departing from the spirit or the scope of this invention, but what I claim as new is:

1. A hat holder comprising a front supporting panel, a substantially U-shaped yoke hingedly connected at its lower edge to the panel, means for limiting the outward swinging movement of the yoke and yielding lips carried by the inner side edges of the yoke for engaging a hat crown.

2. A hat holder comprising a front supporting panel, a U-shaped yoke hingedly connected at its lower end to the panel and movable to an operative position at an angle to said panel, means for limiting the outward swinging movement of the yoke on the panel and bent back lips on the inner edges of the upright portions of the yoke for resiliently engaging a hat crown when the same is placed in the yoke.

3. A hat holder comprising a front supporting panel, a U-shaped yoke hingedly connected at its lower end to the panel and movable to a collapsed position within the plane of said panel and to an operative position at an angle to said

panel, and arms hingedly connected to the panel having inwardly directed fingers engaging the outer face of the yoke to limit the outward swinging movement of said yoke.

5. A portable hat holder or shelf comprising a front panel, a substantially U-shaped yoke hingedly connected at its lower edge to the panel and adapted to swing toward and away from the panel, means for limiting the outward swinging movement of the yoke at the upper end thereof, the yoke at its hinge connection with the front panel being provided with a connecting portion projecting outwardly from the plane of the panel, and a bent down tab carried by said connecting portion engaging the outer face of said panel.

ERNEST W. PFEIL.
